W. E. WREAD

DOOR LATCH AND LOCK

Filed Aug. 27, 1923

Witness:
W. M. Gentle.

UNITED STATES PATENT OFFICE.

WILLIAM E. WREAD, OF LOS ANGELES, CALIFORNIA, ASSIGNOR, BY MESNE ASSIGNMENTS, TO WREAD PRODUCTS CORPORATION, A CORPORATION OF CALIFORNIA.

DOOR LATCH AND LOCK.

Application filed August 27, 1923. Serial No. 659,529.

An object of this invention is to provide a door latch and lock that can be made easily and quickly at low cost; that is simple to construct and assemble, and that is strong and durable, and easy to repair.

Another object is to provide a latch and lock that can be installed in a door with a less expenditure of time and labor and without the exercise of mechanical skill heretofore required for installation of locks in doors.

An object is to provide a lock that can be applied to a door by simply boring two parallel holes in place of a mortise. That is to say, this newly invented lock and latch has a case comprising a rim plate and two tubes that are insertable into holes that can be bored with an ordinary straight bit.

A feature of the invention is shown in the construction whereby the latch is provided with a reversible bolt.

The invention is shown in the exceedingly simple lock which comprises just four parts inclusive of the casing.

Features of the invention are shown in the novel construction, combination and arrangement of the parts whereby a new latch and lock of pleasing and simple appearance is produced.

An object is speed in the installation of door latches and locks.

The invention is broadly new, basic and pioneer in that it comprises an apertured face plate or bar adapted to the face of a door jamb and two elongated bolt casings each fixed at its outer end to the inner face of said bar and bolts operating in their respective elongated bolt casings and the apertures of the face plate or bar.

Other objects, advantages and features of invention may appear from the accompanying drawing, the subjoined detail description and the appended claims.

The accompanying drawing illustrates the invention.

Figure 1 is a fragmental edge view of a door with a latch and lock attached thereto that is constructed in accordance with this invention; the parts being shown about half size.

Fig. 2 is a side view of the latch and lock about three-fourths actual size assembled and ready to attach to a door.

Fig. 3 is a plan view of Fig. 2.

Fig. 4 is a full size fragmental cross section on line α^4 , Figs. 2 and 8.

Fig. 5 is a full size fragmental cross section on line α^5 , Figs. 2 and 8.

Fig. 6 is a fragmental inside view of the face plate showing the boss to which the casing of the latch is attached.

Fig. 7 is an end elevation of the latch casing.

Fig. 8 is a fragmental section on line α^8 , Fig. 1, enlarged to actual size showing the latch bolt in latching position and the lock bolt in unlocked position and the key in place.

Fig. 9 is a fragmental section analogous to and on the same scale as Fig. 8 with the latch and lock bolts in altered position.

Fig. 10 is a plan view of the lock dog.

Fig. 11 is a combined side and end view of a latch dog.

Fig. 12 is a combined side and edge view of the lock key.

The appliance consists of an apertured bar or plate 1 having an outer and inner face, and to the inner face is detachably connected two cylindrical elongated casings 2, 3 for containing the parts of the latch and lock mechanisms.

Integral with the plate 1 and extending rearwardly therefrom are the bosses 4, 5, having rectangular openings therethrough; and to these bosses the casings 2, 3 are detachably connected; and in the outer walls of these bosses and adjacent to the plate 1 are cut oppositely arranged concentric grooves 6 that are adapted to receive the oppositely disposed lugs 7 on the ends 8 of the cylindrical casings 2, 3; and the bosses are provided with oppositely disposed channels 9 in the outer walls that extend from the free end of the bosses into the eccentric grooves 6 so that the ends 8 of the casings can be fitted over the bosses with the lugs 7 in channels 9 and moved toward plate 1 until the lugs are seated in the open end of the grooves 6 after which the cylindrical casings are turned on their axis about ninety degrees to seat the lugs 7 in the closed ends of the grooves 6 and hold the casings in a fixed position.

When the casings 2, 3 are so attached to the bosses 4, 5 the cross opening 10 in casing 2 and the key hole 11 in casing 3 are arranged perpendicular to the sides of the appliance.

95

105

- Within the cylindrical casing 2 there is arranged the reversible latch bolt 12 that has a beveled end slidable through the rectangular opening 13 through the plate 1 and boss 4, and this bolt is provided with a shoulder 14 for engaging the free end of boss 4 and limiting the outward movement of the bolt. The other end of bolt 12 is forked thereby forming tines that are placed astride the squared cross bolt 15 to which are detachably secured the door knobs 16. The bolt 12 is reversible in that it can be removed, turned over and replaced in the casing to a reversed latching position.
- 15 The casing 2 adjacent the openings 10 has opposite portions of the wall bent inward toward its axis to form bearing surfaces for the latch dogs 17 that are loosely mounted on the cross bolt 15.
- 20 These dogs have hubs in the outer walls of which are cut the concentric grooves 18 into which are milled the flattened bearing edge 19 of the casing 2, and the hubs of the dogs are fitted therein so that they turn easily and freely when the cross bar 15 is rotated; and are also rotatably secured in place so that the bar 15 can be removed without displacing them.
- 25 Cross pins 20 are extended through the tines of the latch bolt 12 in position to be engaged by the dogs 17 when they are rotated; by which engagement the bolt 12 is moved back against the tension of spring 21 that is interposed between the closed end 30 22 of casing 2 and a washer 23 abutting the forked end of bolt 12.
- 35 By the foregoing construction and arrangement of parts the bolt 12 will be moved back against the tension of spring 20 whenever the knobs 16 are turned to rotate the cross bolt 15 in either direction thereby moving the extended beveled end of the latch bolt to a position entirely within the appliance so that it will be released from the usual corresponding catch member associated with a latch but not shown as it is of common construction and forms no part of this invention; and when the knobs are released the spring 20 returns the bolt 20 to latching position. That is, the beveled end of the bolt is forced out by tension of the spring into latching position.
- 40 Within the cylindrical casing 3 is arranged the lock bolt 24 that has a rectangular reduced end that is adapted to slide through the rectangular opening 25 through the plate 1 and boss 5, and this bolt has a shoulder 26 that is adapted to engage the free end of the boss 5 and limit the outward movement of the bolt.
- 45 Rearward of the shoulder 26 the bolt 24 is reduced to the form of a plate the thickness of which is varied slightly in the different locks so that a key for one lock cannot effectively operate in another, and through

this plate there is cut a key way 27 in which opening there is a key contacting nib 28 with two corresponding surfaces that are engaged by either of the edges 29 of a key 30 to move the bolt 24 longitudinally of the casing 3.

50 A recess having notches 31, 32 is cut into the bolt 24 in position to be engaged by the catch 33 of the lock dog 34.

The dog 34 is pivoted on the pin 35; and it is formed with sides spaced apart a width sufficient for them to move freely up or down on opposite sides of the reduced portion of bolt 24; and so that the catch 33 at their free ends will alternately engage the notches 31, 32 and hold the bolt 80 in a fixed position or until the catch 33 is disengaged from the notches.

85 The catch 33 is lifted out of the notches 31, 32 by means of a pair of extensions 36 on the key 30.

90 When the key is turned in the opening 27 a pair of the extensions 36 pass upward on opposite sides of the flat portion of bolt 24 and engage the under edges of the dog 34 and lift the free end thereof to disengage the catch 33 from either one or the other of the notches 31, 32, after which one of the edges 29 of the key 30 engages one or the other surfaces of the nib 28 to force the bolt 24 either into locking or unlocking 95 position.

99 A spring 37 is provided for holding the dog 34 toward the bolt 24.

100 The end of the casing 3 is closed by a screw plug 38.

105 The appliance is attached to a door by first mortising a shallow rectangular recess 39 in the front edge 40 of a door 41 after which two parallel holes 42, 43 of slightly greater diameter than the cylindrical casings 2, 3 and of the same distance apart are bored in the front edge of the door at a proper place within the recess 39 to receive the casings 2, 3.

110 Also two cross holes are bored from the sides of the door to intersect the holes 42, 43 at proper places for the cross bolt 15 and key hole 11, and the appliance is secured in place by the counter-sunk screws 44 that pass through the plate 1 and into the wood 115 of the door 41.

115 The appliance can be attached to any door in the manner described, and if desired it can be provided with ornamental side plates 45 secured in place in the usual way.

120 The installation consists of first mortising a rectangular recess of proper dimensions as previously stated to receive the face plate 1 after which the recessing for the other parts are accomplished by the use of an auger of proper diameter; by which means the latch and lock can be attached to a door.

125 I claim:

1. A door lock comprising a plate having a boss formed therein; a cylindrical cas- 130

ing detachably connected to said boss, said plate and boss having an opening therethrough, a lock bolt in said casing having one end slidable in said opening; a shoulder 5 formed on said bolt adapted to engage the free end of said boss to limit the outward movement of said bolt, said bolt having a key way provided therein and forming a key contacting nib and corresponding surfaces at each side of said nib, said nib adapted for engagement with the edge of a key to move said bolt longitudinally of the casing; said bolt formed with a recess having oppositely disposed notches, and a dog pivotally mounted in said casing and adapted 15 for engagement with the said notches to hold the bolt in adjusted position.

2. A door lock comprising a plate having a boss formed thereon; a cylindrical casing 20 detachably connected to said boss, said plate and boss having an opening therethrough, a lock bolt arranged in said casing and having one end adapted to be slidable in said opening; a shoulder on said bolt adapted 25 to engage the free end of said boss to limit the outward movement of said bolt; said bolt being formed with a key way and providing an actuating nib and corresponding surfaces at each side of said nib, said nib 30 adapted for engagement with a key to move

said bolt longitudinally of the casing; said bolt further provided with a recess having oppositely disposed notches formed therein; a pin extending through said casing; a dog pivoted on said pin; a catch on said dog 35 adapted for engagement with said notches to hold said bolt in extended position and for releasing the bolt when the said key engages the said nib in either direction.

3. A lock for doors comprising a plate 40 having an outer and inner face; a cylindrical casing detachably connected to the inner face of said plate; a lock bolt operable in said casing and being formed with a recess; a key way intersecting said recess, a nib 45 formed in said recess and having corresponding surfaces adapted for engagement with a key inserted in the key way to move the bolt longitudinally of the casing, said bolt formed on its upper edge with a recess having oppositely disposed notches provided therein and a dog pivoted in said casing and having a catch adapted for engagement with the notches to hold said bolt in extended 50 position. 55

In testimony whereof, I have hereunto set my hand at Los Angeles, California, this 18th day of January, 1923.

WILLIAM E. WREAD.
